HORACE L. COLE, OF SHARON, PENNSYLVANIA, ASSIGNOR TO WESTINGHOUSE ELECTRIC & MANUFACTURING COMPANY, A CORPORATION OF PENNSYLVANIA

TRANSFORMER WINDING

Application filed June 8, 1928. Serial No. 283,890.

My invention relates to electrical transformers and particularly to the arrangement and connections of the windings of transformers.

In the operation of transformers, it is often desirable to have a source of voltage and current proportional to that supplied to the transformer but of lower magnitude so that the power supplied or delivered by the transformer may be measured by measuring the power supplied by low-voltage and low-current conductors. In practice, it has been difficult to obtain a winding to deliver both low current and low voltage and of sufficient reactance to insure safe operation upon the occurrence of a short circuit of the winding.

In auto transformers, and, especially, when tap-changing devices are employed to vary the effective number of turns near the end of the transformer winding, and, upon the occurrence of surges in the power supply circuit, heavy surges may be caused to flow directly from the line into the transformer through the end turns of the windings.

There is danger of excessive voltage reaching the tap changer and terminal connections when there are relatively few end turns between the line and the tap changer. When used in windings that require tap changers or other devices to be placed near the line leads, my invention interposes additional surge impedance between the line and the part to be protected, without materially affecting the normal operating characteristics of the transformer.

An object of my invention, generally stated, is to provide means for limiting the flow of current in transformer windings during abnormal operating conditions.

A further object of my invention is to provide a transformer winding of high internal reactance and capable of delivering a low voltage and low current.

Another object of my invention is to provide surge or short-circuit protection to a transformer winding.

Other objects of my invention will become apparent to those skilled in the art when

the following description is considered in conjunction with the accompanying drawings, in which,

Figure 1 of the drawings is a diagrammatic view of a transformer having a tertiary winding connected in accordance with my invention; 55

Fig. 2 is a diagrammatic view of the windings and connections of the transformer shown in Fig. 1; 60

Fig. 3 is a diagrammatic view of an auto transformer in which a number of turns are reversed in accordance with my invention; and 65

Fig. 4 is a diagrammatic view of the windings and connections of the auto transformer shown in Fig. 3.

In the transformer shown in Fig. 1, a primary or high-voltage winding 10 is wound upon a core 11 and may have its terminals connected to a suitable source of alternating-current power. The secondary winding 12 consists of a less number of turns than the primary winding 10 and may, therefore, be considered as a low-voltage winding. The secondary winding 12 is so disposed upon the core 11 that energy delivered to the primary winding 10 from its source of supply is transferred to the secondary winding 12, in a manner well known in the art, to energize a supply line at a lower voltage than that to which the primary winding 10 is connected. 70 75 80

An auxiliary or tertiary winding 13 is wound upon the core 11 and is disposed to supply a relatively low current at low voltage, for the operation of meters and other devices requiring relatively low kva. to operate, the power delivered by the tertiary winding 13 being proportional to that of the main windings. The tertiary winding 13 is composed of 85 90

two coils 14 and 15, which are connected together in series relation, but are so wound upon the core 11 that the voltage induced in the coil 14 is always opposite to that induced in the coil 15. The terminal voltage of the tertiary winding 13 is, therefore, the difference between the voltage induced in the coil 14 and the voltage induced in the coil 15, and the winding 13 thereby provides a voltage of 95 100

low value from a winding of a relatively great number of turns which is adequately protected against short circuits and of sufficient reactance to permit its safe and efficient

6 operation.

From an inspection of Fig. 2, the relation between the magnitudes of the voltages induced in the windings 10, 12 and 13 will be readily apparent. The winding 10 supplies 10 energy to both the windings 12 and 13, and the ratio of transformation between the various windings is proportional to the turns of the corresponding windings, as is well known in the art. Furthermore, it will be apparent 15 that, with the coils 14 and 15 connected in the relation shown, and with the coil 14 comprising a few more turns than the coil 15, as shown, the voltages induced therein will be in opposite directions so that the resultant 20 voltage will be a voltage equivalent to only a few turns of the winding 14. The provision of the coil 15, therefore, causes additional reactance in the tertiary winding 13 and enables the tertiary winding to produce a low 25 voltage and a low current.

When such tertiary winding is used for metering purposes, as is often desired, the disposition of the winding on the core with respect to the main windings may be so made 30 that, when the main windings are loaded and delivering power, the tertiary voltage will be proportional to the voltage of one or the other windings. In this way, the tertiary may be used for measuring the power on the primary 35 side or on the secondary side, if so designed, giving a safe and reliable source of potential without the use of a special potential transformer.

The auto transformer shown in Figs. 3 and 40 4 comprises a core 16, which may be of the shell type, about which a plurality of coils are wound. The source of primary voltage is connected between the conductors 17 and 18 and energizes the complete winding comprising 45 the several windings or sections 19, 20, 21 and 22, all of which are connected in series-circuit relation.

The secondary or low voltage of the auto 50 transformer is taken from the conductors 17 and 23 and may be varied by connecting any of the taps 24 with any of the taps 25, thereby disconnecting and bypassing a portion of section 20, or section 21, of the transformer winding, or a portion of each, and, in this 55 way, reducing the number of effective turns connected between the primary leads 17 and 18. While, in the figure and throughout the description, the windings connected between the conductors 17 and 18 have been designated 60 as the primary and those between 17 and 23, the secondary, the auto transformer may be operated with the windings between 17 and 18 as the secondary and those between 17 and 23 as the primary, with the same effect, so far 65 as the invention is concerned. The operation

of tap-changing devices is well known in the art, and, therefore, it is deemed unnecessary to embody a full description of their operation herein.

As will be seen from the diagrams, the combination of the sections 19, 20 and 21 of the winding will constitute the main or effective portion of the transformer winding, that is, the portion which will govern the direction of the voltage between the leads 17 and 23. The auxiliary winding 22 is of opposite polarity to the sections 19, 20 and 21 and is connected in series with the sections 19, 20 and 21 adjacent to the section 21, between the section 21 of the transformer winding and line conductor 18.

By the connection of a section of winding, such as 22, having a polarity opposite to that of the main transformer winding in series-circuit relation with an auto transformer, it is possible to protect the end turns of the transformer winding from any surges which may occur in the supply line.

From the diagram of Fig. 4, it will be apparent that, with the voltage difference represented by the distance between the conductors 23 and 18, it will be difficult to provide a tap-changing device to satisfactorily control the magnitude of this variable voltage without placing the tap-changing connections so close to the end turns of the winding and thus so reducing the reactance between the conductors 23 and 18 that operation of the device would be unsafe upon the occurrence of a power surge or other abnormal condition. The application of the section of winding 22, therefore, facilitates variation in the voltage delivered to the conductors 17 and 23, as well as affords protection from line surges to the tap-changing mechanism and to those turns of the coils 20 and 21 which have been bypassed through the operation of a tap-changer mechanism.

Since it will be possible to modify the embodiments set forth and adapt them to numerous applications without departing from the spirit and scope of my invention, it is intended that the foregoing description shall be construed as merely illustrative and not in a limiting sense.

I claim as my invention:

1. In a transformer, a variable winding provided with voltage-changing taps, said staps being disposed to control the end turns of the effective winding, an auxiliary winding section of opposite polarity to the variable winding, connected in series relation therewith between the tapped end of said winding and the transformer terminal for increasing the reactance in series with the tap-controlled sections of the winding to protect them against voltage surges.

2. In a transformer, a winding comprising sections inductively related to each other, said winding sections each comprising a plu-

rality of turns connected in series-circuit relation, two adjacent winding sections being provided with taps for varying the points of connection therebetween, one of said winding sections being connected between said tapped sections and the terminal of the transformer having turns oppositely disposed with respect to the turns of the other winding sections, whereby the terminal voltage of said 10 winding is the difference in the voltages induced in the oppositely disposed turns.

In testimony whereof, I have hereunto subscribed my name this 29th day of May, 1928.
